UNITED STATES PATENT OFFICE.

GEORGE FREDERIC RIEGEL, OF NEW YORK, N. Y., ASSIGNOR TO PINAUD INCORPORATED, OF NEW YORK, N. Y., A CORPORATION OF NEW YORK.

DESIGN FOR A CARTON.

Application filed May 8, 1928. Serial No. 26,606. Term of patent 14 years.

To all whom it may concern:

Be it known that I, GEORGE FREDERIC RIEGEL, a citizen of the United States, and a resident of the borough of Manhattan, city, county, and State of New York, have invented a new, original, and ornamental Design for a Carton, of which the following is a specification, reference being had to the accompanying drawing, forming a part thereof.

Fig. 1 is an elevation looking at two sides of the carton;

Fig. 2, is an elevation looking at the third side of the carton;

Fig. 3 is a perspective view looking down upon the top of the carton; and

Fig. 4 is a perspective view looking at the bottom of the carton.

I claim:

The ornamental design for a carton as shown.

G. FREDERIC RIEGEL.
